[57] CLAIM

The ornamental design for a pencil holder for use on a golf bag, or similar article, substantially as shown and described.

DESCRIPTION

FIG. 1 is a front isometric view of a pencil holder for use on a golf bag, or similar article showing my new design;

FIG. 2 is a rear isometric view thereof;

FIG. 3 is an enlarged side elevational view, the opposite side being a mirror image thereof;

FIG. 4 is a front elevational view thereof;

FIG. 5 is a rear elevational view thereof;

FIG. 6 is a top plan view thereof; and,

FIG. 7 is a bottom plan view thereof.

FIG. 1.

FIG. 2.

FIG. 3.

FIG. 4.

FIG. 5.

FIG. 6.

FIG. 7.
